SMELTER

George A. La Voie, Long Beach, Calif.

Application February 19, 1934, Serial No. 711,968

6 Claims. (Cl. 266—27)

This invention relates to a smelter whereby metals are released from their ores or sands and are collected in a melted state, the slag or dross being continuously withdrawn as the smelter operates.

An object of my invention is to provide a smelter utilizing oil burners for heat, the incoming charge being continuously fed into the smelter thru a hopper.

Another object is to provide a smelter which will effectively handle ores or sands without first preheating or roasting the ores in order to remove moisture. In my smelter, this operation is accomplished within the smelter itself, thereby eliminating time and labor.

A further object is to provide a novel feeding arrangement for the ore whereby a portion of the hot gases introduced into the smelter are diverted against the bottom of the hopper, thereby drying the charge.

A further object is to provide a novel construction and arrangement of the oil burners so that the charge is effectively heated.

Other objects, advantages and features of invention may appear from the accompanying drawings, the subjoined detailed description, and the appended claims.

In the drawings

Figure 1 is a side elevation of my smelter, a portion of the outlet tunnel and stack being shown in section.

Figure 2 is a top plan view of the smelter.

Fig. 3 is a sectional view taken on line 3—3 of Fig. 4.

Figure 4 is a longitudinal sectional view of the smelter.

Figure 5 is a front elevation of the smelter.

Figure 6 is a fragmentary sectional view taken on line 6—6 of Fig. 4.

Figure 7 is a sectional view taken on line 7—7 of Fig. 1.

Referring more particularly to the drawings, my smelter 1 comprises side walls 2, 3, a front wall 4 and a rear wall 5. An arch 6 forms the top or roof of the smelter and extends longitudinally thereof. A hopper 7 extends thru the arch 6 and the ore to be smelted is first placed in the hopper.

A pair of spaced baffle walls 8, 9 is provided within the smelter, and a bed 10 is positioned between the walls 8, 9. This bed slopes towards one corner so that the metal and slag can be easily withdrawn, as will be further described.

An opening 11 is provided in the front wall 4 and at the bottom of said wall, for the purpose

of admitting air into the smelter. Ore is fed from the hopper 7 into the bed 10 thru a vertical chute 12. The lower face of the chute 12 is arched, as shown at 13, and the rear edge thereof is closer to the bed 10 so as to constrict the flow of the gases. The purpose of this constriction will be further described.

An opening 14 is provided in the front wall 4, and an oil burner 15 extends therethru. The opening is flared on the inside so that the burner 15 can be adjusted and its flame directed to the point desired within the smelter.

Openings 16, 17 are provided in the walls 2, 3, respectively, and burners 18, 19 extend into the openings 16, 17, respectively. These openings are positioned adjacent the baffle wall 8 and are flared on the inside so that the burners can be adjusted and the flame from these burners directed to the desired point within the smelter. A second burner opening 16' is provided below the opening 16 to enable a burner to be placed closer to the bed 10, if necessary. Auxiliary burner openings 20, 21 are provided in the walls 2, 3, respectively, adjacent the baffle wall 9. The purpose of these auxiliary openings is to enable the burners 18 or 19 to be moved if the slag should become cool on the bed 10 and refuse to flow downwardly to the outlet.

The hot gases, after moving over the bed 10, pass downwardly thru the outlet 22, into the tunnel 23, and thence to the stack 24. If desired, the tunnel 23 is widened adjacent to the stack 24 and water is sprayed onto the exhaust gases thru pipes 25. The water dissolves the noxious materials in the gases and flows thru outlets 26 in the floor of the tunnel, and thence to the sump 27.

A suction fan 28, of usual and well known design, pulls the gases thru the tunnel 23, and thence into the stack 24.

As previously stated, the chute 12 constricts the flow of gases over the bed 10. The purpose of this construction is to force some of the hot gases upwardly into the passage 29. This passage extends upwardly and against the bottom of the hopper 7. The by-pass ducts 30, 31 extend from the passage 29 around the chute 12, and thence into a passage 32, which last named passage opens into the smelter back of the chute. A damper 33 is provided in the passage 32 to control the quantity of hot gases which flow therethru. By means of this by-pass arrangement, the ore is preheated in the hopper 7, and moisture is removed therefrom before it enters the chute 12.

As previously stated, the bed 10 is inclined towards one corner, and a metal outlet hole 34 is provided in the wall 2. Slag holes 35 are also provided in the wall 2 above the hole 34, and the slag will flow almost continuously from these last named holes.

The burners 15, 18 and 19 burn continuously, and the hot gases from these burners are directed against the cone of ore which is formed between the chute 12 and the bed 10. As the metal and slag melt, additional quantities of ore will move downwardly into the chute 12, while the melted products spread over the bed 10. The metal being the heaviest, rests on the bottom and eventually flows out of the hole 34. The lighter slag floats on top and flows out of the holes 35.

The side walls of the smelter are suitably reinforced by structural steel members 36, 37. These structural members are arranged so as to absorb the stresses in the side walls.

Having described my invention, I claim:

1. A smelter comprising side walls, front and rear walls, a top arch, spaced baffle walls, a bed between the baffle walls, a hopper, a chute depending from the hopper, said chute being adapted and arranged to deposit material upon the bed, an air passage in the front wall, oil burners extending thru the side walls and the front wall whereby heat is supplied to the smelter, said chute extending across the smelter and projecting into the space above the bed whereby a constricted passage is formed above the bed for the hot gases, said hopper having an upwardly extending passage therein, and by-pass ducts extending from the passage around the chute, said passage and ducts conveying hot gases against the bottom of the hopper whereby moisture is removed from the charge.

2. A smelter comprising side walls, front and rear walls, a top arch, front and rear baffle walls in the smelter, an inclined bed extending between said baffle walls, each of said side walls having a burner opening therein adjacent the front baffle wall and adjacent the rear baffle wall, said front wall having a burner opening therein, a burner in the front wall and a burner in each of the side walls, a hopper, a chute depending from the hopper and projecting into a space above the bed and transversely of the smelter, the bottom face of the chute being arched transversely and inclined longitudinally whereby a flow constriction is provided above the bed for the hot gases, said hopper having a by-pass passage extending adjacent the bottom thereof, and by-pass ducts extending from said passage around the chute whereby the bottom of the hopper and the charge therein are heated.

3. A smelter comprising side walls, front and rear walls, a top arch, a pair of spaced transversely extending baffle walls in the smelter, an

inclined bed extending between said baffle walls, a hopper, a chute depending from the hopper, said chute extending transversely of the smelter and into a space above the bed and between the baffle walls whereby a constricted passage is formed above the bed for the hot gases, said side walls having burner openings therein between the baffle walls, burners projecting thru said openings, a burner opening in the front wall, a burner projecting thru said last named opening, and an air passage in the front wall adjacent the bottom thereof.

4. A smelter comprising side walls, front and rear walls, a top arch, a pair of spaced transversely extending baffle walls in the smelter, an inclined bed extending between said baffle walls, a hopper, a chute depending from the hopper, said chute extending transversely of the smelter and into a space above the bed and between the baffle walls whereby a constricted passage is formed above the bed for the hot gases, said side walls having burner openings therein between the baffle walls, burners projecting thru said openings, a burner opening in the front wall, a burner projecting thru said last named opening, an air passage in the front wall adjacent the bottom thereof, said hopper having an upwardly extending passage in the bottom thereof and by-pass ducts extending from the passage around the chute, said passage and ducts conveying hot gases against the bottom of the hopper whereby moisture is removed from the charge.

5. A smelter comprising side walls, front and rear walls, a top arch, spaced baffle walls, a bed between the baffle walls, said bed being inclined, a hopper, a chute depending from the hopper, said chute being adapted and arranged to deposit material upon the bed, an air passage in the front wall, oil burners extending through the side walls and the front wall whereby heat is supplied to the smelter, said chute extending across the smelter and projecting into the space above the bed whereby a constricted passage is formed above the bed for the hot gases.

6. A smelter comprising side walls, front and rear walls, a top arch, spaced baffle walls, a bed between the baffle walls, said bed being inclined, a hopper, a chute depending from the hopper, said chute being adapted and arranged to deposit material upon the bed, an air passage in the front wall, oil burners extending through the side walls and the front wall whereby heat is supplied to the smelter, said chute extending across the smelter and projecting into the space above the bed, the lower surface of said chute being arched transversely of the smelter and inclined longitudinally of the smelter whereby a constricted passage is formed above the bed for the hot gases.
